UNITED STATES PATENT OFFICE.

ALBERT LEISEL, OF NEWBURGH, NEW YORK.

MACHINE FOR DOUBLING FABRICS.

1,133,440.

Specification of Letters Patent. Patented Mar. 30, 1915.

Application filed April 17, 1912. Serial No. 391,273.

To all whom it may concern:

Be it known that I, ALBERT LEISEL, a citizen of the United States of America, residing in Newburgh, in the county of Orange and State of New York, have invented certain new and useful Improvements in Machines for Doubling Fabrics, of which the following is a specification.

This invention relates to an improved machine for doubling fabrics by which two different kinds of fabrics, such as leather, imitation-leather, mohair and the like, can be united with a backing layer of cotton or other fabric by means of a waterproof cement so as to be capable of resisting wear and the influence of the atmosphere in a higher degree than the covering or face-fabrics alone; and the invention consists more specifically of certain improvements in the machine for doubling fabrics, for which Letters Patents No. 1,042,129 were granted to me on October 22, 1912, so that the waterproof cement employed for uniting the two layers of fabric can be applied in a more effective manner and the construction of the machine rendered less complicated and more efficient in use; and for this purpose the invention consists of a machine for doubling fabrics in which the doctor by which the waterproof cement is applied to one of the fabrics to be doubled or united to the other fabric is combined with the abutments arranged at opposite ends of the heated pressing-rolls for the fabric and heated up while being applied to the fabric by a steam-heating pipe located in close proximity to the doctor and the liquid waterproof cement; and the invention consists further of certain details of construction which will be fully described hereinafter and finally pointed out in the claims.

In the accompanying drawings, Figure 1 represents a side-elevation of my improved machine for doubling fabrics, Fig. 2 is a vertical longitudinal section of the same, on line 2—2, Fig. 3, Fig. 3 is a plan-view of the machine, Fig. 4 is a detail vertical transverse section, on line 4—4, Fig. 3, through the doctor used for regulating the supply of liquid waterproof cement to one of the fabrics to be united, said figure also showing the abutments for holding the waterproof cement supplied to the fabrics; Fig. 5 is a detail vertical section of the scraper used in connection with each one of the heated compression-cylinders for building-up or

uniting the two layers of fabric, and Fig. 6 is a detail top-view of one end of the scraper, shown in Fig. 5, and one of its adjusting screws.

Similar letters of reference indicate corresponding parts throughout the several figures of the drawings.

Referring to the drawings, *a*, *a*¹ are two hollow-rolls which are located sidewise of each other in the supporting-frame *f* and which are heated by means of live steam admitted to the interior of the rolls by steam supply-pipes *b* that are connected with the interior steam-pipes *b*¹ at one end of the rolls, the steam being carried off by suitable exhaust-pipes *b*² at the interior of the heating-pipes *b*¹ at the end of the supporting-frame *f*. The heated roll *a* is supported in bearings of stationary standards of the supporting-frame *f*, while the heated roll *a*¹ is supported in bearings of horizontally-adjustable slide-rests *d*¹ which are guided on the frame *f*, so the roll *a*¹ can be adjusted closer or farther away from the stationary roll *a* for providing for the different thicknesses of the fabrics to be united. The adjustment of the movable roll *a*¹ is accomplished by means of screws *d*² having hand-wheels *d*³, said screws acting on the slide-rests of the roll *a*. The rolls *a*, *a*¹ are rotated at the same speed and in opposite direction to each other from a driving-shaft *s* which is supported in suitable bearings in the side-standards of the frame *f* below the rolls and by intermediate driving gear-wheels *g*, *g*¹, respectively on the driving-shaft and a short intermediate shaft, *s*¹ supported in bearings of the side-standards *f*¹ and gear-wheels *g*² and *g*³ on the rolls *a*, *a*¹ respectively. The two layers of fabric to be united are wound up on reels, the shafts of which are supported in bearings *e*, *e*¹ at the opposite ends of the frame *f* and conducted over suitable guide-rolls *c*² and *c*³ and adjustable tension-rolls *e*⁴, *e*⁵ to the heated rolls *a*, *a*¹, and then between the same in downward direction over a guide-roller *e*⁶ to a suitable conveyer (not shown) by which the double fabrics after they are united by the rolls *a*, *a*¹ are conducted off. The bearings of the tension-rolls *e*⁴, *e*⁵, are adjustable by means of slide-rests *e*⁷, *e*⁸, which are acted upon by hand-operated screws *e*⁹, so as to apply a regulating tension to both layers of fabric.

At the ends of the heated rolls *a*, *a*¹ are

located vertical abutments h , the lower ends of which extend by means of arc-shaped tapering lower portions h^1 into contact with the roll a , the arc-shaped portions being arranged in close proximity to the heads of the roll a . The abutments h are supported on downwardly-extending inclined recessed plates h^2 which serve also for supporting an adjustable block i that extends transversely from one side-standard f^1 of the frame f to the other and to the face of which is attached by means of fastening-screws an inclined doctor i^1 that is adapted to be adjusted closer or farther away from the heated roll a , according to the different thicknesses of the face-fabric to be doubled-up or the layer of cement to be supplied to the backing fabric, by means of screws h^5 having hand-wheels h^6 at their upper ends, said screws being threaded in suitable keepers h^4 attached to the inclined supporting-plates h^2 and the lower ends of which are swiveled into the upper ends of the guide-block i , as shown in Fig. 4. The recessed abutments h are supported on the upper ends of the guide-block i and rigidly attached thereto by means of clamping bolts h^3 which are applied to the upper rear-ends of the abutments, as shown in Fig. 4. The inclined supporting-plates h^2 and the keepers h^4 for the adjusting screws are firmly attached to the upper part of the side-standards f^1 of the supporting frame f . The abutments h , h^1 and the doctor i^1 form with the roller a , and the fabric thereon, a trough to hold the liquefied waterproof cement. The inclined screws h^5 enable the doctor to be adjusted radially of the roller, thereby regulating the thickness of the layer of cement placed thereon, and enable adjustment for different thicknesses of fabric, and for wear of the edge of the doctor. The waterproof cement is supplied to the trough referred to in heated and liquefied condition and is kept in this condition so as to enter the pores of the fabric to be coated by means of a steam-heated pipe p which is located in a longitudinal recess i^2 at the lower end of the guide-block i in close proximity to the lower portion of the doctor. The live steam is supplied at one end to the supply pipe p^1 and conducted off at the opposite end of the same through the pipe p^2 , as shown in Figs. 1 and 3. The cement is spread uniformly over the surface of the covering-fabric and is then firmly united with the backing fabric by the pressure exerted on both the covering or face-fabric and the backing fabric by the heated pressure-rolls during the passage of said fabric between the same, the two layers after being doubled or united being then conducted off below the heated rolls by passing over the roller e^6 on to the conveyor for drying.

Below the heated rolls a , a^1 and in con-

tact with the lower circumference of the same, are arranged scrapers l , l^1 which extend across the full length of the rolls between the side-standards f^1 , said scrapers being held into close contact with the surface of the heating rolls so as to remove any traces of cement that should be pressed through the minute openings or meshes of the fabric on to the surface of the same, or that portion of the cement that should run over the edges of the fabric passing over the roll a , so that the surface of the heated rolls is kept absolutely clear of even the slightest traces of cement and thereby the surfaces of the doubled-up fabric kept likewise perfectly clear of cement. The scrapers l , l^1 are supported on transverse guide-blocks l^2 of rectangular cross-section that are supported in the upper portions of holders l^3 which have rectangularly-recessed lower portions l^4 that are bolted to the transverse bars, l^5 supported by the side-frame f . The scrapers l^1 are applied to guide-blocks l^2 and adjusted to the lower surface of the heating-rolls a , a^1 by set-screws l^6 having hand-wheels l^7 at their lower ends, as shown clearly in Figs. 5 and 6.

For preventing the bending of the scrapers l , l^1 midway of their length and holding them in intimate contact with the heated rolls, auxiliary holders l^8 are arranged at one or more points intermediately of the length of the scrapers, said auxiliary holders being likewise supported on the transverse bars l^2 and prevented from turning thereon owing to the rectangular shape of the bars and the corresponding recesses of the holders.

The cement that is removed by the scrapers from the surface of the rolls is collected in a suitable receptacle (not shown) at the lower part of the frame below the scrapers and returned from time to time into the trough-shaped space between the fabric on the heated roll a , abutments h and doctor i , or it may be mixed with a new quantity of cement and supplied therewith into the said trough-shaped space, the doctor acting in the nature of a scraper for supplying the waterproof cement to the fabrics to be doubled-up or united.

Any suitable fabrics may be doubled-up by the machine, such as artificial leather and mohair, and a suitable backing fabric, said doubled-up fabric being used for upholstering purposes for the tops of automobiles, and for other purposes. The fabrics are doubled up by the heated rolls as a uniform pressure is exerted on the same as they are passed through the rolls and as the cement is supplied in a slightly-heated liquefied condition to the fabrics, they are uniformly doubled-up and at the same time dried to a considerable extent so that further artificial drying is not required. The properly

doubled fabrics are wound up on a suitable roller and ready for immediate shipment and use.

I claim:

5. 1. A machine for doubling fabrics, comprising a pair of rotary heated rolls, means for guiding two layers of fabrics from opposite sides to and over said rolls, abutments located at opposite ends of one of said heated rolls, the lower ends of said abutments extending into close proximity with said roll, a doctor between the abutments, an adjustable guide-block supporting the abutments and doctor, and a steam-pipe extending along the lower end of said guide-block in close proximity to the lower end of the doctor.
2. A machine for doubling fabrics, comprising a pair of rotary heated rolls, means for guiding two layers of fabrics from opposite sides to and over said rolls, abutments located at opposite ends of one of said heated rolls, the lower ends of said abutments extending into close proximity to said roll, a doctor between said abutments, an adjustable guide-block supporting said doctor and said abutments, a steam-pipe extending along the lower end of said guide-block in

close proximity to the lower end of the doctor, and means for adjusting the guide-block and abutments relatively to the fabric on the heated roll.

3. A machine for doubling fabrics, comprising a pair of rotary heated rolls, means for guiding two layers of fabric from opposite sides to and over said rolls, abutments located at opposite ends of said heated rolls, the lower arc-shaped ends of said abutments extending into close proximity with said roll, a doctor between the abutments extending over said roll an adjustable guide-block supporting said doctor and abutments a steam-pipe extending along the lower end of said guide blocks, supporting plates for said block, means for adjusting the doctor and guide-block relatively to said heated roll, and a steam-pipe located in a recess of the lower end of the guide-block in close proximity to said doctor.

In testimony that I claim the foregoing as my invention, I have signed my name in presence of two subscribing witnesses.

ALBERT LEISEL.
